UNITED STATES PATENT OFFICE

PHILIP DAVIDSON, OF NEW YORK, N. Y., ASSIGNOR TO INTERNATIONAL COMBUSTION ENGINEERING CORPORATION, OF NEW YORK, N. Y., A CORPORATION OF DELAWARE

CENTRAL LUBRICATION SYSTEM FOR ROLLER-MILL ROLLERS

Application filed November 8, 1928. Serial No. 318,070.

This invention relates to a new and improved central lubricating system for the bearings of the several rollers of a pulverizing mill of the general type shown, for example, in the patent to Raymond et al. 1,573,191, granted February 16, 1926. In a mill of this type, a plurality of pulverizing rollers are pivotally suspended in a circular series, from a frame or spider which rotates about a vertical axis in a closed mill housing, the rollers swinging out by centrifugal force against the inner surface of a fixed circular bull-ring, whereby the material caught between the ring and rollers is pulverized. An outlet is provided in the upper portion of the housing through which the pulverized material is withdrawn in suspension in air, by means of any suitable suction system. Means is provided for suspending each individual roller from the spider so that it may rotate about its own axis, and also swing into engagement with the bull-ring, and a self-contained lubricating system is usually provided for supplying lubricant to the bearings which rotatably support the roller. According to the present invention, improved means are provided for distributing lubricant from a single central reservoir, located outside of the mill, to the several bearings of each individual roller.

Briefly described, the invention provides a hollow distributing head mounted coaxially with the vertical shaft which supports the spider and rollers, the lower portion of this head being divided into a plurality of distributing chambers, symmetrically arranged about the axis of rotation, and each distributing chamber being connected with the bearings of one of the rollers by a suitable conduit. A stationary conduit leads from the reservoir into the mill and has a portion projecting along the axis of rotation of the shaft into the distributing head, a suitable sealing means being provided between the rotating head and stationary shaft for preventing the entry of pulverized material into the distributing head at this point. The lower end of the stationary conduit is provided with an offset portion or nozzle for discharging the lubricant in a continuous stream into the sev-

eral distributing chambers which are revolving beneath the nozzle.

The principal object of the invention is to provide an improved central lubricating system for a pulverizing mill of this type as disclosed and claimed hereinafter.

Another object is to provide improved means for distributing lubricant from a stationary reservoir to a plurality of rotating distributing chambers or conduits.

Another object is to provide improved means for preventing the entry of dust or other material into the lubricating system.

Another object is to provide improved means for lubricating the central vertical shaft of the mill, from the same system that lubricates the revolving rollers.

Other objects and advantages of this invention will be more apparent from the following detailed description of one approved form of the apparatus.

In the accompanying drawings:

Fig. 1 is a central vertical section through the assembled mill and lubricating apparatus.

Fig. 2 is a plan view, on a somewhat larger scale, of the rotating assembly in the mill, the upper cover portion of the mill being removed.

Fig. 3 is a vertical section through the distributing head, this view being taken substantially on the line 3—3 of Fig. 4.

Fig. 4 is a horizontal section through the distributing head, taken substantially on the line 4—4 of Fig. 3.

Fig. 5 is an elevation, partially in vertical section, of one of the air vents and air-cleaning means.

The invention is here shown as applied to a roller pulverizing mill comprising a base or supporting framework 1 from which rises a central pedestal 2, in which is journaled the main central driven shaft 3. Shaft 3 is rotated by means of a beveled gear 4 fixed to its lower end and meshing with a bevel pinion 5 on a drive shaft 6. Mounted on the upper end of shaft 3 is the spider 7 from which are suspended the pulverizing rollers indicated generally at 8. In the present example, there are six of these rollers hung at equally

spaced intervals about the periphery of the spider 7 so that they may rotate on their own axes and also swing in vertical planes passing through the axis of the shaft 3. When the 5 assembly is rotated, the rollers swing outwardly by centrifugal force against the fixed bull-ring 9, the pulverizing rollers 10 rolling along the inner surface of this bull-ring to pulverize the material which is introduced 10 by any suitable feeding means such as indicated at 11, mounted in the enclosing mill housing 12. A rotating skirt or shield 13 is suspended from spider 7 between the rollers and the pedestal 2 and a plurality of plows 15 15 carried by this skirt help to feed the material between the rollers 10 and bull-ring 9 so that it may be pulverized. The pulverized material is drawn off in suspension in air through the outlet pipe 15 connected with the 20 top of casing 12, any suitable form of suction fan or other means being utilized to withdraw the air and suspended pulverized material.

The spider 7 is formed with a plurality of 25 outwardly projecting yokes 16, each of which comprises a pair of parallel arms 17 and 18 in which are pivotally mounted the ends of the trunnion shaft 19. The rocker 20 comprises two split collars positioned at right 30 angles to one another, the collar 21 being clamped about the trunnion shaft 19 by means of bolts 22 and the collar 23 being clamped about the upper portion of the roller supporting assembly by means of bolts 35 24. At 25 is indicated generally the housing supported from collar 20, in which the shaft and bearings for rotatably supporting the roller 10 are mounted. This housing also usually contains a lubricating system for 40 supplying lubricant to the shaft bearings. The specific manner in which the roller is journaled, and the specific self-contained lubricating system used form no part of this invention. The present invention relates to 45 a means for continuously supplying oil- or other lubricant from a stationary reservoir located outside the mill to the individual lubricating systems contained in the housings 25 of the several revolving roller assemblies. 50 By means of this central lubricating system, lubricant is continuously and automatically distributed to the several roller units while the mill is in operation, so that the supply of lubricant in each roller assembly will be automatically replenished as it is used.

An oil tank or reservoir 26 is positioned on any suitable stationary support 27 located outside of and above the mill housing. An 55 outlet pipe or conduit 28 provided with a cut-off valve 29 leads from the lower portion of tank 26. At 30 is indicated the filling opening provided with a suitable closure, and 31 indicates an air vent for admitting air to the tank as the lubricant flows out. A suitable form of air vent is indicated in Fig. 5,

70 consisting of an inverted pipe loop 31, one end of which is connected with tank 26 and the other end connected with a housing 32 containing a quantity of metallic packing 33 soaked in oil. An inlet opening 34 permits the entry of air which is strained or cleaned by its passage through the material 33 before being drawn through pipe 31 into the tank 26. This device serves to keep the lubricating system clean by straining out the coal-dust or other impurities from the air that enters the system. At 35 is shown an oil gauge for indicating the amount of lubricant in tank 26.

75 The outlet pipe or conduit 28 extends downwardly at 36 and is provided with an adjustable needle valve 37 and a sight feed device 38. At the lower end of vertical pipe 36, a horizontal extension 39 projects through the wall 12 of the mill housing into the mill chamber. An air vent 40, similar in all respects to the device 31 previously described and shown in detail in Fig. 5, is connected in the oil feed conduit outside of the mill at the juncture of the vertical pipe 36 80 and horizontal pipe 39.

85 On the upper end 41 of the central vertical driven shaft 3 of the mill is positioned the distributing head indicated generally at 42. This head comprises a lower cup-shaped portion 43 adapted to fit over the upper end 41 of shaft 3 and be secured thereto by means of a plurality of screw bolts 44 or any other suitable fastening means. The upper portion of head 42 houses a closed cylindrical chamber 45, which is closed at the bottom by horizontal wall or partition 46 and at the top by the upper horizontal wall or roof 47 of the head. In the lower portion of chamber 45, a plurality of vertical partitions 48 project radially 90 from the central axis of rotation 49 of the head 42 and shaft 3, so as to form a plurality of oil-distributing chambers 50 which are positioned symmetrically about the axis of rotation 49. One of these distributing chambers 95 50 is provided for each of the roller assemblies 8. An outlet or distributing pipe 51 leads from the lower portion of each chamber 50, and is connected by a section of flexible piping 52 with the inlet pipe 53 leading to the self-contained lubricating system of one 100 of the roller assemblies 8.

105 An extra distributing chamber 54 may be provided in head 42 for delivering oil to the bearings of vertical shaft 3. A drain passage 55 in the bottom 46 of the distributor head aligns with a passage 56 formed in the upper end portion 41 of the shaft 3, this passage 56 leading to the bearings 57 in pedestal 2. The 110 chamber 54 will ordinarily be considerably smaller than one of the distributing chambers 50, the relative sizes of these chambers depending upon the relative amount of oil needed by the bearings 57 of the central shaft 3 115 120 125 130

and the bearings in one of the roller assemblies 8.

A vertical conduit member 58 is clamped at 59 in a bracket 60 mounted in the mill housing, so that the center line of conduit 58 will be positioned in alignment with the extended axis of rotation 49 of the distributing head and shaft 3. The upper end of stationary conduit 58 is connected by a section of flexible piping 61 with the feed conduit 39 which projects through the wall 12 of the mill, so that the vertical conduit 58 forms an extension of the supply conduit 28 leading from reservoir 26. The lower end of conduit 58 projects through a stuffing box 62 in the top 47 of the distributing head, and within the chamber 45 is provided with a laterally projecting discharge extension or nozzle 63 which projects radially so as to discharge the oil or other lubricant into the outer wider portions of the several distributing chambers 50 and 54.

The stuffing box 62 is of a usual construction comprising a member 64 screwed at 65 into the top 47 of the distributing head and having a central chamber 66 containing the packing material 67. The upper end of chamber 66 is open to admit the gland 68 which is adjustably forced down by bolts 69 so as to force packing 67 into engagement with the stationary conduit 58 and the revolute member 64. This packing box serves to seal the joint between these relatively rotating parts so as to prevent the entry of dust or other pulverized material in the mill into the lubricating system.

In operation, the oil will feed downwardly by gravity from reservoir 26 through feed conduit 28, the rate of flow being regulated by the needle valve 37 and observed in the sight feed device 38. The oil flows downwardly through pipes 36, 39, 61 and 58 into the rotating distributing head and is discharged from nozzle 63 into the distributing chambers 50 and 54 which successively pass beneath the nozzle. Since the head is continuously rotating at an even rate, each of the chambers 50 will remain an equal length of time beneath the discharge nozzle 63 and will receive an equal proportion of the lubricant discharged from the nozzle. The smaller distributing chamber 54 will receive a relatively smaller proportion of the lubricant for satisfying the relatively smaller need of the bearings 57 of shaft 3. While the oil will be intermittently added to each chamber 50, a sufficient supply will be maintained in this chamber to provide a steady flow, if need be, through distributing pipes 51 and 52 to the oil distributing system in the roller assembly 8.

In normal operation, a certain amount of air will be drawn in through the vent 40 thus creating a slightly excessive air pressure in the distributing chamber 45, and this air can only escape through the stuffing box 62 or through

the lubricating systems of the several roller assemblies 8. This escaping air will tend to prevent the entry of coal-dust or other pulverized material through the stuffing box 62, or the packed joints in the roller assembly 8. The fact that the pulverized material is withdrawn by suction from the mill chamber tends to lower the pressure in the mill chamber thereby facilitating the outward flow of air from the lubricating system through stuffing box 62, as just described. In this way, the lubricating system is maintained comparatively free from dust or other foreign materials. The air drawn into the lubricating system is cleaned by the strainers 33 in the air vents 31 and 40.

It will be apparent that this central lubricating system is quite simple, has comparatively few parts, and is easy to operate. It is only necessary that the reservoir 26 be filled at intervals, and the needle valve 37 adjusted to provide the proper flow of lubricant to the distributing head. The system distributes an equal quantity of oil to each of the roller journals, and a properly proportioned quantity to the bearings of the central driven shaft, all of this being accomplished automatically and without any necessary adjustments.

I claim:

1. In an oiling system for pulverizing mills, a distributing head adapted to rotate about its central vertical axis, said head comprising an enclosed chamber divided in its lower portion by a plurality of radial partitions into a plurality of distributing chambers arranged symmetrically about the axis of rotation, a conduit leading from each distributing chamber, a relatively stationary reservoir for lubricant, a conduit leading from the reservoir and projecting into the distributing head along the axis of rotation of the head, this conduit having a lateral extension at its lower end for discharging lubricant successively into the rotating distributing chambers.

2. In an oiling system for pulverizing mills, a distributing head adapted to rotate about its central vertical axis, said head comprising an enclosed chamber divided in its lower portion by a plurality of radial partitions into a plurality of distributing chambers arranged symmetrically about the axis of rotation, a conduit leading from each distributing chamber, a relatively stationary reservoir for lubricant, a conduit leading from the reservoir and projecting into the distributing head along the axis of rotation of the head, this conduit having a lateral extension at its lower end for discharging lubricant successively into the rotating distributing chambers, and a stuffing box in the top of the distributing head through which the stationary conduit projects.

3. In an oiling system for pulverizing mills, a distributing head adapted to rotate

- about its central vertical axis, said head comprising an enclosed chamber divided in its lower portion by a plurality of radial partitions into a plurality of distributing chambers arranged symmetrically about the axis of rotation, a conduit leading from each distributing chamber, a relatively stationary reservoir for lubricant, a conduit leading from the reservoir and projecting into the distributing head along the axis of rotation of the head, this conduit having a lateral extension at its lower end for discharging lubricant successively into the rotating distributing chambers, a stuffing box in the top of the distributing head through which the stationary conduit projects, an air vent in said stationary conduit between the reservoir and the head for admitting air to the conduit and an air-cleaner in this vent.
4. In an oiling system for pulverizing mills, a distributing head adapted to rotate about its central vertical axis, said head comprising a hollow cylindrical member closed at its upper end and open at its lower end to be fitted over and secured to the upper end of a rotating vertical shaft, a central horizontal partition forming a closed chamber in the upper portion of the head, a plurality of vertical partitions extending radially from the axis of rotation in the lower portion of the closed chamber to form a plurality of distributing chambers, an outlet conduit leading from each distributing chamber, a relatively stationary reservoir for lubricant, a non-rotary conduit leading from the reservoir and having a portion extending downwardly in line with the axis of rotation of the head and projecting into the closed chamber through an opening in the top of the head, and having a discharge nozzle offset laterally from the axis of rotation, and means for sealing the joint between the rotary head and the non-rotary conduit projecting thereinto.
5. In combination with a stationary lubricant reservoir, means for distributing lubricant from the reservoir to the bearings of a plurality of rotating members having a planetary movement about a central axis comprising a distributing head formed with a plurality of separate chambers positioned symmetrically about the central axis and rotating with the members, a conduit leading from each chamber to the bearings of one of the members, and a stationary conduit leading from the reservoir and having a discharge nozzle positioned at one side of the central axis above the distributing head so that the lubricant will be fed to the chambers in sequence as they rotate beneath the nozzle.
6. In combination with a stationary lubricant reservoir, means for distributing lubricant from the reservoir to the bearings of a plurality of rotating members having a planetary movement about a central axis comprising a distributing head mounted so that its

central axis of rotation coincides with the central axis of the rotating assembly, the head embodying an enclosed chamber divided at its lower part into a plurality of distributing chambers, one for each member, arranged symmetrically about the axis of rotation, a conduit leading from each distributing chamber to the bearings of one of the members, a stationary conduit leading from the reservoir and having a portion projecting through the top of the distributing head into the chamber along the axis of rotation, means for sealing the joint between the rotating head and stationary conduit, the stationary conduit having a laterally projecting discharge nozzle at its lower end adapted to successively feed lubricant into the distributing chambers.

7. In combination with a stationary lubricant reservoir, means for distributing lubricant from the reservoir to the bearings of a plurality of rotating members having a planetary movement about a central axis comprising a distributing head mounted so that its central axis of rotation coincides with the central axis of the rotating assembly, the head embodying an enclosed chamber divided at its lower part into a plurality of distributing chambers, one for each member, arranged symmetrically about the axis of rotation, a conduit leading from each distributing chamber to the bearings of one of the members, a stationary conduit leading from the reservoir and having a portion projecting through the top of the distributing head into the chamber along the axis of rotation, means for sealing the joint between the rotating head and stationary conduit, the stationary conduit having a laterally projecting discharge nozzle at its lower end adapted to successively feed lubricant into the distributing chambers, and a control valve in the stationary conduit.

8. An oiling apparatus for a pulverizing mill, which includes a central drive shaft, bearings for supporting and centering the shaft, a spider carried by the shaft, a fixed bullring centered about the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant, a distributing head mounted coaxially on the drive-shaft and rotating therewith, the head being formed with a plurality of separate chambers, one for each roller, arranged symmetrically about the axis of rotation, a conduit leading from each chamber to the bearings of one of the rollers, and a stationary conduit leading from the reservoir and having a discharge nozzle positioned above the chambers at one side of the axis of rotation of the head.

9. An oiling apparatus for a pulverizing mill, which includes a central drive shaft,

bearings for supporting and centering the shaft, a spider carried by the shaft, a fixed bullring centered about the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant, a distributing head mounted coaxially on the drive-shaft and rotating therewith, the head embodying an enclosed chamber divided at its lower part into a plurality of distributing chambers arranged symmetrically about the axis of rotation, a conduit leading from each distributing chamber to the bearings of one of the rollers, a stationary conduit leading from the reservoir and having a portion projecting through the top of the distributing head along the axis of rotation, means for sealing the joint between the rotating head and the stationary conduit, this conduit having a laterally projecting discharge nozzle at its lower end adapted to successively feed lubricant into the distributing chambers.

10. An oiling apparatus for a pulverizing mill, which includes a central drive shaft, bearings for supporting and centering the shaft, a spider carried by the shaft, a fixed bullring centered about the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant, a distributing head mounted coaxially on the drive shaft and rotating therewith, the head embodying an enclosed chamber divided at its lower part into a plurality of distributing chambers arranged symmetrically about the axis of rotation, a conduit leading from one of these chambers through the shaft to the shaft bearings, separate conduits leading from each of the other chambers to the bearings of the respective rollers, a stationary conduit leading from the reservoir and having a portion projecting along the axis of rotation through the top of the distributing head, and means for sealing the joint between the rotating head and the stationary conduit, this conduit having a laterally projecting discharge nozzle at its lower end adapted to successively feed lubricant into the distributing chambers.

11. An oiling apparatus for a pulverizing mill which includes a mill housing having an outlet through which pulverized material is withdrawn by suction, a central drive shaft, bearings for supporting and centering the shaft, a bullring centered about the shaft, a spider on the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant positioned outside of the mill housing, a distributing head mounted coaxially on the drive-shaft so as to rotate therewith, the head enclosing a chamber divided in its lower part into a plurality of distributing chambers, one for each roller, arranged symmetrically about the axis of rotation, a conduit leading from each distributing chamber to the bearings of one of the rollers, a stationary conduit leading from the reservoir into the chamber and having a portion extending along the axis of rotation into the distributing head and having a laterally projecting discharge nozzle at its lower end positioned to successively feed lubricant into the distributing chambers, a stuffing box in the top of the distributing head through which the stationary conduit projects, and an air vent in the stationary conduit outside of the mill housing.

12. An oiling apparatus for a pulverizing mill which includes a mill housing having an outlet through which pulverized material is withdrawn by suction, a central drive shaft, bearings for supporting and centering the shaft, a bullring centered about the shaft, a spider on the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant positioned outside of the mill housing, a distributing head mounted coaxially on the drive-shaft so as to rotate therewith, the head enclosing a chamber divided in its lower part into a plurality of distributing chambers, one for each roller, arranged symmetrically about the axis of rotation, a conduit leading from each distributing chamber to the bearings of one of the rollers, a stationary conduit leading from the reservoir into the chamber and having a portion extending along the axis of rotation into the distributing head and having a laterally projecting discharge nozzle at its lower end positioned to successively feed lubricant into the distributing chambers, a stuffing box in the top of the distributing head through which the stationary conduit projects, and an air vent in the stationary conduit outside of the mill housing.

13. An oiling apparatus for a pulverizing mill which includes a mill housing having an outlet through which pulverized material is withdrawn by suction, a central drive shaft, bearings for supporting and centering the shaft, a bullring centered about the shaft, a spider on the shaft, a plurality of pulverizing rollers suspended from the spider and adapted to swing out by centrifugal force against the bullring, and a plurality of bearings for rotatably supporting each roller from the spider, said oiling apparatus comprising a stationary reservoir for a supply of lubricant positioned outside of the mill housing, a distributing head mounted coaxially on the drive-shaft so as to rotate therewith, the head enclosing a chamber divided in its lower part into a plurality of distributing chambers, one for each roller, arranged symmetrically about the axis of rotation, a conduit leading from each distributing chamber to the bearings of one of the rollers, a stationary conduit leading from the reservoir into the chamber and having a portion extending along the axis of rotation into the distributing head and having a laterally projecting discharge nozzle at its lower end positioned to successively feed lubricant into the distributing chambers, a stuffing box in the top of the distributing head through which the stationary conduit projects, and an air vent in the stationary conduit outside of the mill housing, and an air-strainer in said vent.

izing rollers suspended from the spider and adapted to swing out by centrifugal force against the bullring, and a plurality of bearings for rotatably supporting each roller from the spider, said oiling apparatus comprising a reservoir for a supply of lubricant positioned outside of the mill housing, a distributing head mounted coaxially on the drive-shaft so as to rotate therewith, the head enclosing a chamber divided in its lower part into a plurality of distributing chambers, arranged symmetrically about the axis of rotation, a conduit leading from one of these chambers to the bearings of the shaft, separate conduits leading from each of the other distributing chambers to the bearings of the several rollers, a stationary conduit leading from the reservoir into the mill chamber and extending along the axis of rotation into the distributing head, a stuffing box in the top of the head through which the conduit projects, this conduit having a discharge nozzle at its lower end projecting laterally so as to successively feed lubricant into the several distributing chambers, and an air vent in the stationary conduit outside of the mill housing.

14. An oiling apparatus for a pulverizing mill which includes a mill housing having an outlet through which pulverized material is withdrawn by suction, a central drive shaft, bearings for supporting and centering the shaft, a bullring centered about the shaft, a spider on the shaft, a plurality of pulverizing rollers suspended from the spider and adapted to swing out by centrifugal force against the bullring, and a plurality of bearings for rotatably supporting each roller from the spider, said oiling apparatus comprising a reservoir for a supply of lubricant positioned outside of the mill housing, a distributing head mounted coaxially on the drive-shaft so as to rotate therewith, the head enclosing a chamber divided in its lower part into a plurality of distributing chambers, arranged symmetrically about the axis of rotation, a conduit leading from one of these chambers to the bearings of the shaft, separate conduits leading from each of the other distributing chambers to the bearings of the several rollers, a stationary conduit leading from the reservoir into the mill chamber and extending along the axis of rotation into the distributing head, a stuffing box in the top of the head through which the conduit projects, this conduit having a discharge nozzle at its lower end projecting laterally so as to successively feed lubricant into the several distributing chambers, an air vent in the stationary conduit outside of the mill housing, and an air-strainer in the vent.

PHILIP DAVIDSON.
